Primary Examiner — Cathron C Brooks*Assistant Examiner* — Sharon S Oum(74) *Attorney, Agent, or Firm* — Ladas & Parry LLP(57) **CLAIM**

The ornamental design for two-axis stabilizer, as shown and described.

DESCRIPTION

FIG. 1 is a perspective view of a two-axis stabilizer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof shown in an alternative position; and,

FIG. 9 is a front, bottom, left perspective view thereof showing the two-axis stabilizer ready for use.

The broken lines illustrate portions of the two-axis stabilizer that form no part of the claimed design.
